Primary Examiner — Cathron Brooks*Assistant Examiner* — Aula Soroush(74) Attorney, Agent, or Firm — Banner & Witcoff, Ltd.(57) CLAIM

The ornamental design for a shoe outsole, as shown and described.

DESCRIPTION

FIG. 1 is a front perspective view of a shoe outsole showing my new design;

FIG. 2 is a bottom view thereof;

FIG. 3 is a rear perspective view thereof; and,

FIG. 4 is an enlarged view of the claimed portion shown in FIG. 1, show in isolation.

The broken lines immediately adjacent to the shaded area represent the bounds of the claimed design, and form no part thereof. The unshaded region within the shaded area forms no part of the claimed design. The broken lines showing the remainder of the shoe are for environmental purposes only and form no part of the claimed design.
